UNITED STATES PATENT OFFICE.

DELBERT W. NORTHRUP, OF BROOKLINE, MASSACHUSETTS.

UNION FABRIC.

1,122,990.

Specification of Letters Patent. Patented Dec. 29, 1913.

Application filed August 4, 1914. Serial No. 854,951.

To all whom it may concern:

Be it known that I, DELBERT W. NORTHRUP, citizen of the United States, residing at Brookline, in the county of Norfolk and 5 State of Massachusetts, have invented new and useful Improvements in Union Fabrics, of which the following is a specification.

My invention relates to textile fabrics, and its objects are to produce a union cloth 10 of new texture, to preserve the durability of the cloth while at the same time increasing the attractiveness of its appearance, and to utilize by a combination of materials a new result not heretofore obtained by each. 15 My invention primarily consists in inter-weaving woolen or worsted yarns with cotton yarns together with additional threads of fiber silk to give a spotted and brilliant effect to the goods and to reinforce the cloth 20 and preserve its durability, these materials being united so as to present on the face of the goods a woolen or worsted background displaying at regular intervals spots of fiber silk, and on the back of the goods 25 a surface largely of cotton.

My invention further consists in the improvements and novel arrangements of material hereinafter more particularly described and claimed. 30 It has been common in the manufacture of shoes for many years to employ in the construction of the upper as a substitute for leather, textile fabrics of various kinds. In view of the rough usage to which it is 35 likely to be exposed the cloth employed for this purpose must be durable and have good wearing qualities. The cloth should also at all times present an attractive appearance. To produce a fabric which is able 40 to withstand exposure to the weather, and the wear and tear to which a shoe upper must necessarily be subject, and at the same time to display and preserve an ornamental aspect has been heretofore a question of 45 much study and in general of unsatisfactory solution. Where the ornamental appearance of the cloth has been attained, it has been at the sacrifice of the wearing qualities of the upper; and where the cloth 50 has been of the durable character desired the decorative quality has been dispensed with. So far as I know, I am the first person to utilize for the cloth of a shoe upper, a combination of woolen or worsted 55 and cotton yarns and yarns of fiber silk

in such proportions and in such arrangement as fully to accomplish the object of my invention.

Attention is hereby directed to the drawing in which similar numerals of designation refer to similar parts throughout the several views.

Figure 1, is a view of the face of my improved fabric showing the arrangement of the spots of fiber silk; Fig. 2, is an enlarged 60 view of portion of Fig. 1 showing the arrangement of the yarns; and Fig. 3, is a cross section on line 3—3 of Fig. 1.

Referring to the drawing, the fabric 4 is 70 constructed of warp yarns 5 and the weft 75 yarns 6 and 7. The warp yarns 5 are preferably of woolen or worsted material and in the completed fabric substantially cover the spaces between the spots and form the background on the face of the goods 80 and furnish a wearing and protective surface. The weft yarns 6 are vegetable in origin, preferably cotton or linen and are woven as shown to form a filling and in large part a backing for the cloth, and to 85 furnish tensile strength and resiliency to the fabric. The weft yarns 7 are fiber silk; these yarns are laid as shown to produce a spotted appearance upon the face of the goods, and serve not only to ornament the 90 cloth but also to add greatly to its durability and utility.

By the combination of material above set forth, I combine in one fabric a decorative appearance without in the slightest degree 95 eliminating the wearing qualities essential to the durability of my improved cloth when used for shoe uppers, for which the fabric is particularly designed. Preferably I use substantially an equivalent quantity by weight 100 of each of the warp and weft yarns, the latter being supplied in the proportion of approximately one half fiber silk and one half of the other material used for the filling.

While I have described and shown a particular arrangement of warp and weft yarns, I by no means desire so to limit my invention. Any arrangement of the yarns, whether as warp or woof yarns, forming 105 a woven fabric in which wool is used to construct the face thereof with additional warp or woof yarns of fiber silk to give a spotted effect, and in which cotton or similar material is used to aid in forming the 110

filling and back, is within the spirit and scope of my invention.

What I claim and desire to secure by Letters Patent is---

5 A union fabric composed of interwoven wool warp yarns, and cotton and fiber silk weft yarns, the wool yarns forming the face of the material, said silk yarns appearing thereon in the shape of spots, and the cot-

ton yarns substantially aiding in forming in the filling and back of said fabric.

In testimony whereof I have hereunto set my hand in presence of two subscribing witnesses, this 3rd day of August 1914.

DELBERT W. NORTHROP.
